NEW YORK.

NASAL DEVICE.

1,143,731.

Specification of Letters Patent. Patented June 22, 1915.

Application filed March 8, 1915. Serial No. 12,796.

To all whom it may concern:

Be it known that I, FREDERICK W. SCHOONMAKER, Jr., a citizen of the United States, and a resident of Montclair, in the county of Essex and State of New Jersey, have invented certain new and useful Improvements in Nasal Devices, of which the following is a specification.

The object of the invention is to provide an inexpensive device whereby ointment or the like can be applied to the interior of the nose in a convenient and effective manner. This is accomplished by the simple construction and combination which will now be briefly described.

In the drawings forming a part hereof: Figure 1 is a perspective view illustrating the use of the device; Fig. 2 is a longitudinal section through the nostril tube and bulb, the upper portion of the collapsible container being shown in elevation screwed into the lateral branch of the tube; and Fig. 3 is a fragmentary elevation of the container, closed.

The device includes a short, comparatively wide tube 1 adapted to enter the outer end of either nostril, as indicated in Fig. 1. As shown, this tube is of substantially the same internal diameter throughout, that is to say, the passage is preferably not substantially narrowed at the discharge end. At its rear end it is formed with a conventional head 2, which enables the retention of an elastic rubber bulb 3. In addition it is provided with a short lateral branch 4, which is inclined rearward, that is to say, from the discharge end toward the bulb end, and this branch is internally screw-threaded, so that it may receive the threaded nozzle 5 of a collapsible container 6. This container or tin tube is of the well-known character and when disconnected from the branch 4 is closed by a screw cap 7.

To use the device, the cap is removed from the container, and the nozzle of the latter screwed into the branch, as shown in Fig. 2. Then by gentle pressure on the collapsible container, a suitable amount of the ointment is forced into the branch 4 and thence into the tube 1, where it may pass into the bulb 3. The tube now being applied to the nostril in a convenient manner, a sharp pressure on the bulb drives the ointment into the nasal passage.

What I claim as new is:

1. Means for introducing ointment into the nose, comprising a short tube adapted to enter the nostril, and having a free and unobstructed passage therethrough, an elastic bulb on the rear end of said tube, a short lateral branch on the tube having a free and unobstructed passage therethrough, and a collapsible container for the ointment adapted to be secured to the free end of said branch, whereby ointment may be pressed from said container through the branch into the tube and thence, by compression of said bulb, forced into the nostril.

2. Means for introducing ointment into the nose, comprising, in combination, a collapsible container for the ointment having a screw-threaded nozzle, a short tube adapted to enter the nostril, an elastic bulb on the rear end of said tube, and a short lateral rearwardly inclined branch on the tube, screw threaded for the reception of the nozzle of the container.

In testimony whereof I have signed my name in the presence of two subscribing witnesses.

FREDERICK W. SCHOONMAKER, JR.
